Primary Examiner — Kendra Leslie Hamilton*Assistant Examiner* — Jameson P Carey(74) *Attorney, Agent, or Firm* — Foley & Lardner LLP(57) **CLAIM**

The ornamental design for an oral irrigation device as shown and described.

DESCRIPTION

FIG. 1 is a front-left perspective view of an oral irrigation device showing the new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The dashed lines depict portions of the oral irrigation device that form no part of the claimed design.
